UNITED STATES PATENT OFFICE.

PURNELL W. SMITH, OF PHILADELPHIA, PENNSYLVANIA.

SALT AND PEPPER CELLAR.

No. 846,256.

Specification of Letters Patent.

Patented March 5, 1907.

Application filed March 22, 1906. Serial No. 307,356.

To all whom it may concern:

Be it known that I, PURNELL W. SMITH, a citizen of the United States, residing at Philadelphia, county of Philadelphia, and 5 State of Pennsylvania, have invented a certain new and useful Improvement in Salt and Pepper Cellars, of which the following is a specification.

My invention relates to a new and useful 10 improvement in salt and pepper cellars, and has for its object to provide an exceedingly simple and effective device of this description; and a further object of my invention is to provide means for jarring the perforated 15 top when the cellar is shaken, so as to prevent it from clogging and always permit the contents to be readily sifted therefrom.

With these ends in view this invention consists in the details of construction and 20 combination of elements hereinafter set forth and then specifically designated by the claim.

In order that those skilled in the art to which this invention appertains may understand 25 how to make and use the same, the construction and operation will now be described in detail, referring to the accompanying drawing, forming a part of this specification, in which—

30 Figure 1 is an elevation of a salt-cellar made in accordance with my improvement; Fig. 2, a detail section of the top, showing the means for jarring the same when the cellar is used. Fig. 3 is a section of the lower 35 portion of the cellar, showing the counter-balancing weight therein for righting the cellar when it is upset.

In carrying out my invention as here embodied, A represents a salt-cellar which may 40 be made of glass or any suitable material, the bottom B of which is in the general form of a

section of a sphere, and in this bottom is molded or otherwise secured the weight C, which may be of lead or other heavy material, so that should the cellar be upset this 45 weight will be sufficient to cause the cellar to resume its upright position, as will be readily understood.

D is the top, which may be secured to the body in any manner, such as by screwing 50 thereon, and the upper surface of this top is perforated, as indicated at E, and has depending therefrom a small tube F, in which is confined a ball or other suitable weight G. The tube F is formed integral with the top D. 55

In practice when the cellar is used the ball G will fly back and forth with the shaking of the cellar, first striking upon the inner end of the tube and then upon the perforated section of the cover and at each blow giving a 60 sharp vibration to the cover which will keep the salt or other contents from packing and cause it to pass through the perforations. The tube F is hermetically closed and thereby prevents the salt or other material within 65 the cellar from having access thereto and thus interfere with the movement of the ball G confined therein.

Having thus fully described my invention, what I claim as new and useful is— 70

In combination, a receptacle, a perforated top therefor, a tube depending from the top and formed integral therewith, and a ball within the tube, said tube being hermetically closed. 75

In testimony whereof I have hereunto affixed my signature in the presence of two subscribing witnesses.

PURNELL W. SMITH.
